TWISTING AND PLYING SPINDLE BALLOON CONTROL

Alfred W. Vibber, Ridgewood, N. J.

Application November 9, 1954, Serial No. 467,702

15 Claims. (Cl. 57—58.3)

This invention relates to the control of balloons of strand twisting spindles, particularly spindles of the "in-feeding" type wherein the material in the balloon is drawn from the balloons into the rotating shaft or flyer which creates and maintains the balloon. In a preferred embodiment of the invention it relates to the control of the balloon of the one-spindle twisting and plying system generally of the type shown in Clarkson Patent No. 2,503,242, in which two strands are twisted together so as to form a two-ply strand, a first strand delivered from a supply thereof being ballooned about a let-off strand package from which the second strand is led.

This application is a continuation-in-part of application Serial No. 450,358, filed August 17, 1954.

The present invention presents an improvement over the balloon control devices described in my prior application Serial No. 450,358 in which the means controlling the tension of the first strand in the run thereof between the balloon and the plying junction is a balloon or loop generating means located on the plying shaft or flyer. Although functioning satisfactorily to maintain the balloon in the described range of operating diameter, the devices of my prior application are somewhat complicated in construction, and require the shifting of the balloon generating and balloon diameter detecting means relative to the flyer upon changes in diameter of the balloon. Although the distances through which such means must move relative to the flyer during operation of the device are small, in some instances such movement may throw the plying shaft and flyer undesirably out of balance, particularly when the shaft and flyer rotate at high speed.

The present invention has among its objects the provision of an improved simplified balloon generating shaft-carried control for the balloon of twisting and plying mechanism.

A further object of the invention resides in the provision of the above indicated balloon controlling means in which the parts of the controlling means have their centers of mass fixed with respect to the balloon generating shaft during operation of the device.

A still further object of the invention lies in the provision, in apparatus wherein a first strand is ballooned about a source of supply of a second strand to ply the two strands together, of automatic strand tension control means wholly supported by the twisting and plying shaft of the spindle and wherein the strand at the exit end of the balloon interacts with a strand snubbing member fixed with respect to the shaft, whereby changes in the diameter of the balloon and thus the degree of its wrap-around varies the relative rate of absorption of the two strands into the plied strand.

The above and further objects relating to economies of use and manufacture of the device of the invention will be more readily apparent upon consideration of the following specification.

My invention is clearly defined in the appended claims. Where parts are, for clarity and convenience, referred

2

to on the basis of their oriented position shown in the accompanying drawing, no limitation as to positioning of the entire structure is to be implied, since it will be understood that the entire structure may be inverted or that it may be used in any inclined position. Also in both the description and the claims, parts at times may be identified by specific names for clarity and convenience, but such nomenclature is to be understood as having the broadest meaning consistent with the context and with the concept of my invention as distinguished from the pertinent prior art. The best form in which I have contemplated applying my invention is illustrated in the accompanying drawing forming part of this specification, in which:

Fig. 1 is a somewhat schematic view, partially in side elevation and partially in vertical section, of a preferred embodiment of a one-spindle strand plying mechanism made in accordance with the invention.

Fig. 2 is a view in horizontal section through the flyer of the spindle of Fig. 1, the section being taken along the line 2—2 in Fig. 1.

Fig. 3 is a fragmentary view in vertical section through the flyer of the spindle of Fig. 1, the section being taken along the line 3—3 in Fig. 2.

Fig. 4 is an enlarged, somewhat schematic view in horizontal section of the portion of the flyer at the left in Fig. 2 indicating the interaction between the balloon controlling means on the flyer with the strand entering the flyer from balloons of various diameters.

In the system shown in Figs. 1 and 2, the first strand, designated 10, proceeds from the first let-off package 11 downwardly through positively driven strand feeding means 12 driven in synchronism with the spindle shaft 14, in a manner to be described, into the balloon 15 created by the flyer 16, which constitutes an enlarged head on shaft 14. The strand 10 is drawn in through the flyer and meets the second strand 17 fed from the second let-off package 19 at the point P on the axis of the flyer, the two strands being plied together at point P so as to emerge as the plied strand or cord 20. The cord 20 is taken up by a conventional take-up mechanism 21, preferably one such as shown in Clarkson Patent No. 2,503,242, which withdraws the cord and winds it on bobbin 22 under constant tension.

Taking up now the instrumentalities which operate upon the strand 10 in succession, the first let-off package 11 is preferably rotatably mounted on a support diagrammatically shown in Fig. 1 so as to present the strand 10 opposite the feed-off eye into the strand feeding capstan system 12. Means 12 is made up of a first multi-grooved capstan 25 and a second multi-grooved capstan 26 spaced therefrom, the two capstans being positively geared together so as to rotate at the same speed and in the same direction by means of a gear 27 on capstan 25, a gear 29 on capstan 26, and the intermediate idle gear 30 meshing with the gears on the capstans, all of such mechanism being carried on fixed frame-work (not shown). Means 12, which serves to

deliver the strand 10 to the balloon at essentially constant speed, is positively driven in synchronism with spindle shaft 14 by the worm 31 on the bottom of shaft 14, the worm gear 32 meshing therewith, and mounted on shaft 34, the vertical shaft 35, and the upper horizontal shaft 36, shafts 34, 35, and 36 being geared together, all at a 1x1 ratio, by bevel gears as shown, and shaft 36 being geared to capstan 26, also by bevel gears.

The flyer 16 is in the nature of an enlarged head or flange on the top of the rotatable shaft 14. Shaft 14 is mounted to rotate in bearings 37 in fixed frame parts 39 of the apparatus. The shaft 14 has its outer

surface 40 between frame parts 39 crowned to engage a driving belt (not shown), and serves as a means of creating and maintaining the balloon or free-flying loop 15 in the strand 10, of supporting the second let-off package 19 on top of the flyer 16 in substantially non-rotating position, and of plying the two strands 10 and 17 together at the plying point or junction P. Let-off package 19 is supported on a flange or platform member 41 positioned on the upper, hollow, shaft 42, the lower end of shaft 42 being journalled in the flyer 16 through the medium of the bearing 44. Platform 41 is eccentrically weighted at 45 so that, when the spindle shaft 14 is disposed at a small angle to the vertical the weight 45 will seek the lower position and thus maintain the package 19 and the shaft 42 substantially non-rotating even though flyer 16 rotates at high speed. For ease of illustration the spindle shaft 14 is shown disposed vertically.

The shaft 42 serves also as a support for a means 46 for feeding the strand 17 from package 19 to the plying point P at essentially constant speed. Means 46 consists of a magnetic ball tension device 47 having a non-magnetic seat 49 positioned across the upper end of the shaft 42, the magnetic ball 50 fitting within such seat, the strand 17 progressing between the ball and the seat down into the shaft 42. A magnet 51 positioned beneath seat member 49 maintains the ball 50 stably in its seat. After leaving the magnetic ball tension device, the strand 17 progresses into a radially outer groove on the idle upper multi-grooved feeding capstan 52 journalled horizontally in shaft 42, and thence proceeds downwardly to the confronting radially outer groove of the driven lower multi-grooved capstan 54. Strand 17 then travels from groove to groove between capstans 52 and 54 until it reaches a central groove in driven capstan 54 from which it then travels vertically downwardly to the plying point P.

Capstan 54 is driven in synchronism with the rotation of flyer 16 by means of the central hollow extension shaft 55 of the flyer, shaft 55 carrying a worm 56 on its upper end. Worm 56 meshes with the hourglass worm gear 57 journalled horizontally within shaft 42 at a position radially displaced from the axis thereof. Worm gear 57 has on its outer ends the small pinions 59 which mesh with the larger pinions 60 on the ends of capstan 54. It will be apparent that rotation of the flyer 16 and thus of the shaft 55 relative to the shaft 42 will positively rotate the multi-grooved capstan 54. With the proper choice of sizes and hand of the worm 56 and the worm gear 57, and the proper relative sizes of pinions 59 and 60, the strand 17 will be fed downwardly to the plying point P at the same rate that strand 10 is fed into balloon 15.

The balloon 15 in strand 10 is created and maintained by the flyer 16 shown in Fig. 2. The strand 10 leaving the balloon 15 enters the flyer through a guiding means made up of the automatic tension control, generally designated 61, which functions as a balloon or loop generating means, and the generally radially directed passage 62 which conducts the strand to the plying junction P. The left-hand edge of the flyer (Fig. 2) is horizontally slotted at 64, the slot communicating with means 61 and allowing the strand 10 to assume the various attitudes relative to the flyer from position A to position D (Fig. 4) without contacting any part of the flyer as it first enters such flyer except the first strand snubbing member 65 of means 61. The flyer is suitably slotted at 66 on the right-hand edge (Fig. 2) so that it runs in dynamic balance.

The strand-snubbing member 65, which is preferably made as a part separate from the body of the flyer and from a hard material such as Carboloy, is fixedly and non-rotatably positioned on the flyer so that its strand receiving edge communicates with the slot 64 as shown in Figs. 2 and 3. Member 65 is provided with a central

groove 67 aligned with slot 64 to confine strand 10 vertically in its passage about member 65. Positioned somewhat forwardly of member 65, that is, leading it in the clockwise direction of rotation of the flyer indicated by the curved arrow in Fig. 2 and preferably close to and staggered with relation to member 65, as shown in Fig. 2, is the strand guiding roll 69 which rotates with respect to the flyer on an axis fixed with respect thereto. Roll 69 may thus be said to be fixed with respect to the flyer even though the roll rotates on its axle 70 about its own axis. In the construction shown, roll 69 is journalled on the vertical axle 70 fixed to the flyer, and is provided with ball bearings 71 between the axle and the roll body. Roll 69 has a central grooved portion 72 aligned with the groove on member 65 and further aligned with the passage 62 leading to the plying junction. Because the snubbing member 65 is fixedly positioned on the flyer, and the axis of the strand guiding roll 69 is fixed with respect to the flyer, the center of gravity of neither member 65 nor roll 69 moves with respect to the flyer. The same is true of the tensioning means as a whole made up of member 65 and roll 69, that is, its center of gravity does not move with respect to the flyer.

In its passage inwardly into the flyer the strand 10 is deflected from a straight line path to the point P into a sinuous path by the loop generating and tension controlling means 61, the strand passing about the rearwardly convex surface of member 65, leaving such surface at the point 74 to pass onto the roll 69 and thence through the passage 62 to the point P. The roll 69, being journalled on substantially frictionless bearings, causes virtually no retardation on the strand in its travel regardless of the size of the balloon from which the strand 10 is delivered. Snubbing member 65, however, is so positioned on the flyer and coacts with roll 69 in such manner that it imposes a variable retarding tension on the run 75 of strand 10 approaching point P. The amount of such added tension varies with variations in the diameter of balloon 15 so that it is relatively large when the balloon is of small diameter (1) and is relatively small when the balloon is of large diameter (2).

The run 75 of strand 10, therefore, is subjected to the following total tension $T_{(1)}$ at balloon condition (1):

$$T_{(1)} = T_{\text{balloon (1)}} + t_{\text{added (1)}}$$

and to the following total tension $T_{(2)}$ at balloon condition (2)

$$T_{(2)} = T_{\text{balloon (2)}} + t_{\text{added (2)}}$$

As we have seen,

$$T_{\text{balloon (2)}} > T_{\text{balloon (1)}}$$

If the described means for imposing an added retarding tension on the strand 10 were not employed, the greater tension in the strand in the balloon as the balloon expands, plus the greater friction imposed on it as it contacts the outer rear edge of the radial passage in the flyer due to the increased wrap-around of the balloon, would cause the strand 10 to approach the plying point under increased tension. Under such condition strand 10 acts as a core at the plying point, and more of strand 17 than strand 10 is absorbed into the plied strand or cord 20. Thus the balloon tends to continue to expand, since such prior apparatus is not self-compensating, until it becomes so large as to strike adjoining structures and thus to break.

The described mechanism for imposing a variable added tension on strand 10 is such that the added tension falls off rapidly as the diameter of the balloon increases, so much so that the total tension in strand 10 approaching the plying point decreases on a smooth curve from balloon diameter (1) to balloon diameter (2), in spite of the fact that the tension in the balloon proper increases as balloon diameter increases.

The action of the tension-imposing means 61 will be

more readily understood by a consideration of Fig. 4 wherein it is shown coacting with an incoming strand from a balloon whose diameter varies within the operative range from a small diameter (strand A) to a large diameter (strand D), through two intermediate diameters (strands B and C), the balloon from which strand C leads being larger than that from which strand B leads. This follows from the fact that as the balloon diameter increases the degree of wrap-around of the balloon at the spindle increases, so that the bottom portion of the balloon, leading to the balloon or loop generating and strand tensioning means 61, makes an increased angle with the radius of the flyer as the diameter of the balloon increases.

With a balloon of small diameter (strand A) the strand has its maximum length of contact with member 65, such line of contact subtending the angle a from the initial contact of the strand with member 65 to the point 74, at which it leaves the member. The effective direction of the force which the strand then exerts on member 65 is at a significant angle with respect to the radius of the flyer, and the deviation of the strand by member 65 is at the maximum. Accordingly, the tension (t_A) added by means 61 at such condition of the balloon is at a maximum.

With the balloon at a somewhat increased diameter (strand B) the strand contacts member 65 along a line subtended by angle b , the deviation of strand B by member 65 is less, and the effective direction of the force which the strand then exerts on member 65 is at a smaller angle with respect to the radius of the flyer. Consequently the tension (t_B) added by means 61 at such condition of the balloon is less than t_A .

The same trends in the factors contributing to the tensioning effect of means 61 on the strand are present when it coacts with the strands C and D. Thus the line of contact between strand C and member 65 is shorter than it is with strand B, angle c is smaller than angle b , and the effective direction of the force which strand C exerts on member 65 is closer to the radius of the flyer than it is with strand B.

With strand D the line of contact between the strand and member 65 has a minimum length, angle d is at a minimum, and the effective direction of the force which strand D exerts on member 65 is closer to the radius of the flyer than for any of strands A, B, and C.

As a result of such interaction of the strand being pulled inwardly from the balloon 15 and the tensioning means 61, the added retarding tension on run 75 of the strand approaching the plying point P is at a maximum when the balloon is at its minimum operative diameter, and decreases as the balloon diameter increases, to reach a minimum at the maximum diameter of the balloon. We have seen that the total tension T in run 75 of strand 10 is made up of the instantaneous tension in the strand in the balloon plus the tension imposed thereon by means 61. With the construction shown, the added tension imposed on the run 75 of the strand decreases, as the balloon diameter increases, in increments which are at least equal to those by which the tension of the strand in the balloon proper increases. With appropriate factors such as diameter of the member 65, coefficient of friction of member 65 with the strand 10, and the relative positioning of member 65 and roller 69, so as properly to locate the point 74 and thus to arrive at the desired angles a and d , the total tension T in run 75 of the strand may be made to decrease as the balloon diameter increases. Such latter condition, a decreasing total tension in run 75 of strand 10, is preferred, because of the increased stability of the spindle.

The shape of the curve of total tension in run 75 of strand 10 plotted against balloon diameter can be changed by appropriate changes in the shape of the convex, strand-contacting surface of member 65. Thus such surface may be made, for example, of either parabolic or hyperbolic configuration to yield tensions added to run 75 of strand 75

10 which change in different manners from that existing when member 65 is circular in cross section.

With the apparatus of the invention, therefore, when the balloon diameter increases, the tension in strand 10 approaching the plying point decreases relative to the tension in strand 17. Thus, the strand 17 tends to become the core, more of strand 10 than of strand 17 is absorbed into the plied cord, and the excess strand 10 in the balloon is relatively quickly absorbed into the cord to return the balloon to its optimum diameter within its operating range. When the balloon decreases in diameter from its optimum diameter, the tension in strand 10 approaching point P increases. Strand 10 thus tends to become the core, more of strand 17 than of strand 10 is absorbed into the cord, the strand 10 is withdrawn from the balloon more slowly than it is fed thereinto from package 11 by means 12, and thus the balloon is quickly returned to its optimum diameter.

I claim:

1. Strand twisting mechanism comprising: a source of supply of a strand, a rotatable shaft operable to rotate a loop of the strand, the shaft having a generally radially disposed strand guiding means, means for feeding the strand into the loop, and means for controlling the tension in the generally radial run of the strand, said last named means comprising means to deflect the generally radial run of the strand into a sinuous path at the radially outer portion of the shaft adjacent the loop, the outer end of the sinuous path being directed generally opposite the direction of rotation of the shaft.

2. Strand twisting mechanism comprising: a rotatable shaft operable to rotate a loop of a strand, a source of supply of the strand external of the loop, a first means for feeding the strand into the loop, a second means for feeding the strand out of the loop, the shaft having a generally radially disposed strand guiding means, and means for controlling the tension in the generally radial run of the strand, said last named means comprising loop generating means to deflect the generally radial run of the strand into a sinuous path at the radially outer portion of the shaft adjacent the loop, the outer end of the sinuous path being directed generally opposite the direction of rotation of the shaft.

3. Mechanism for twisting together two strands so as to form a two-ply strand, comprising: a source of supply of a first strand and a support carrying a let-off strand package for a second strand, a rotatable shaft operable to rotate a loop of the first strand about the let-off package and also to ply the two strands together, a first means for feeding the first strand into the loop, a second means for feeding the second strand to the junction where they are plied together, and means for controlling the tension in the run of the first strand approaching the plying junction, said last named means comprising means on the shaft guiding the first strand generally radially inwardly to the plying junction, said guiding means including loop generating means to deflect the first strand into a sinuous path at the radially outer portion of the shaft adjacent the loop, the outer end of the sinuous path being directed generally opposite the direction of rotation of the shaft.

4. Strand twisting mechanism of the infeeding type comprising: a source of supply of a strand, a rotatable shaft operable to rotate a loop of the strand, the shaft having a generally radially disposed strand receiving passage therein, means for feeding the strand into the loop, and means for controlling the tension in the run of the strand in the radial passage in the shaft, said last named means comprising means on the shaft guiding the strand through the radial passage therein, said guiding means including a loop generating means having a convex strand snubbing and guiding member positioned radially outwardly on the shaft, and an idle guiding member the surface of which moves freely with the strand positioned radially inwardly of the snubbing mem-

ber, said two guiding members deflecting the strand into a sinuous path at the radially outer portion of the shaft adjacent the loop, the outer end of the sinuous path being directed generally opposite the direction of rotation of the shaft.

5. Mechanism for twisting together two strands so as to form a two-ply strand, comprising: a source of supply of a first strand and a support carrying a let-off strand package for a second strand, a rotatable shaft operable to rotate a loop of the first strand about the let-off package and also to ply the two strands together, a first means for feeding the first strand into the loop, a second means for feeding the second strand to the junction where they are plied together, and means for controlling the tension in the run of the first strand approaching the plying junction, said last named means comprising means on the shaft guiding the first strand generally radially of the shaft to the plying junction, said guiding means including a loop generating means having a strand snubbing and guiding member positioned radially outwardly on the shaft, and an idle guiding member the surface of which moves freely with the strand positioned radially inwardly of the snubbing member, said two guiding members deflecting the strand into a sinuous path at the radially outer portion of the shaft adjacent the loop, the outer end of the sinuous path being directed generally opposite the direction of rotation of the shaft.

6. Mechanism for twisting together two strands so as to form a two-ply strand, comprising: a source of supply of a first strand and a support carrying a let-off strand package for a second strand, a rotatable shaft operable to rotate a loop of the first strand about the let-off package and also to ply the two strands together, a first means for feeding the first strand into the loop, a second means for feeding the second strand to the junction where they are plied together, and means for controlling the tension in the run of the first strand approaching the plying junction, said last named means comprising means on the shaft guiding the first strand generally radially inwardly of the shaft to the plying junction, said guiding means including a loop generating means having a convex strand snubbing and guiding member positioned radially outwardly on the shaft, and an idle guiding member the surface of which moves freely with the strand positioned radially inwardly of the snubbing member, said two guiding members deflecting the strand into a sinuous path at the radially outer portion of the shaft adjacent the loop, the outer end of the sinuous path being directed generally opposite the direction of rotation of the shaft.

7. Mechanism for twisting together two strands so as to form a two-ply strand, comprising: a source of supply of a first strand and a support carrying a let-off strand package for a second strand, a rotatable shaft operable to rotate a loop of the first strand about the let-off package and also to ply the two strands together, a first means for feeding the first strand into the loop, a second means for feeding the second strand to the junction where they are plied together, and means for controlling the tension in the run of the first strand approaching the plying junction, said last named means comprising means on the shaft guiding the first strand generally radially inwardly of the shaft to the plying junction, said guiding means including a loop generating means having a strand snubbing member with a convex surface facing in the direction opposite the direction of rotation of the shaft, and fixedly positioned radially outwardly on the shaft, and an idle guiding member the surface of which moves freely with the strand fixedly positioned radially inwardly of the snubbing member, said two guiding members deflecting the strand into a sinuous path which passes over the said convex surface of the snubbing member and over the idle guiding member on the side thereof which leads during rotation of the shaft, the first strand passing di-

rectly from the loop into contact with the snubbing member.

8. Mechanism for twisting together two strands so as to form a two-ply strand, comprising: a source of supply of a first strand and a support carrying a let-off strand package for a second strand, a rotatable shaft operable to rotate a loop of the first strand about the let-off package and also to ply the two strands together, a first means for feeding the first strand into the loop, a second means for feeding the second strand to the junction where they are plied together, and means for controlling the tension in the run of the first strand approaching the plying junction, said last named means comprising means on the shaft guiding the first strand generally radially inwardly of the shaft to the plying junction, said guiding means including a loop generating means having a strand snubbing member with a convex surface facing in the direction opposite the direction of rotation of the shaft, and fixedly positioned radially outwardly on the shaft, and an idle guiding member the surface of which moves freely with the strand fixedly positioned radially inwardly of the snubbing member, said two guiding members deflecting the strand into a sinuous path which passes over the said convex surface of the snubbing member and over the idle guiding member on the side thereof which leads during rotation of the shaft, the first strand passing directly from the loop into contact with the snubbing member, the length of the zone of contact between the snubbing member and the strand decreasing as the degree of wrap-around of the loop increases.

9. Mechanism for twisting together two strands so as to form a two-ply strand, comprising: a source of supply of a first strand and a support carrying a let-off strand package for a second strand, a rotatable shaft operable to rotate a loop of the first strand about the let-off package and also to ply the two strands together, a first substantially constant speed means for feeding the first strand into the loop, a second substantially constant speed means for feeding the second strand to the junction where they are plied together, and means for controlling the tension in the run of the first strand approaching the plying junction, said last named means comprising means on the shaft guiding the first strand to the plying junction, said guiding means including means to deflect the strand into a sinuous path at the radially outer portion of the shaft adjacent the loop, the outer end of the sinuous path being directed generally opposite the direction of rotation of the shaft.

10. Strand twisting mechanism comprising: a source of supply of a strand, a rotatable shaft operable to rotate a loop of the strand, the shaft having a generally radially disposed strand receiving passage therein, a first substantially constant speed means for feeding the strand into the loop, and means for controlling the tension in the run of the first strand in the radial passage in the shaft, said last named means comprising means on the shaft guiding the first strand through the radial passage therein, said guiding means including loop generating means having means to deflect the strand into a sinuous path at the radially outer portion of the shaft adjacent the loop, the outer end of the sinuous path being directed generally opposite the direction of rotation of the shaft.

11. Mechanism for twisting together two strands so as to form a two-ply strand, comprising: a source of supply of a first strand and a support carrying a let-off strand package for a second strand, a rotatable shaft operable to rotate a loop of the first strand about the let-off package and also to ply the two strands together, a first substantially constant speed means for feeding the first strand into the loop, a second substantially constant speed means for feeding the second strand to the junction where they are plied together, and means for controlling the tension in the run of the first strand approaching the plying junction, said last named means comprising means on the shaft guiding the first strand generally radially of the

shaft to the plying junction, said guiding means including a loop generating means having a convex strand snubbing and guiding member positioned radially outwardly on the shaft, and an idle guiding member the surface of which moves freely with the strand positioned radially inwardly of the snubbing member, said two guiding members deflecting the strand into a sinuous path at the radially outer portion of the shaft adjacent the loop, the outer end of the sinuous path being directed generally opposite the direction of rotation of the shaft.

12. Mechanism for twisting together two strands so as to form a two-ply strand, comprising: a source of supply of a first strand and a support carrying a let-off strand package for a second strand, a rotatable shaft operable to rotate a loop of the first strand about the let-off package and also to ply the two strands together, a first substantially constant speed means for feeding the first strand into the loop, a second substantially constant speed means for feeding the second strand to the junction where they are plied together, and means for controlling the tension in the run of the first strand approaching the plying junction, said last named means comprising means on the shaft guiding the first strand generally radially of the shaft to the plying junction, said guiding means including a loop generating means having a strand snubbing member with a convex surface facing opposite the direction of rotation of the shaft, and fixedly positioned radially outwardly on the shaft, and an idle guiding member, the surface of which moves freely with the strand, fixedly positioned radially inwardly of the snubbing member, said two guiding members deflecting the strand into a sinuous path which passes over the said convex surface of the snubbing member and over the idle guiding member on the side thereof which leads during rotation of the shaft, the first strand passing directly from the loop into contact with the snubbing member.

13. Mechanism for twisting together two strands so as to form a two-ply strand, comprising: a source of supply of a first strand and a support carrying a let-off strand package for a second strand, a rotatable shaft operable to rotate a loop of the first strand about the let-off package and also to ply the two strands together, a first substantially constant speed means for feeding the first strand into the loop, a second substantially constant speed means for feeding the second strand to the junction where they are plied together, and means for controlling the tension in the run of the first strand approaching the plying junction, said last named means comprising means on the shaft

guiding the first strand generally radially of the shaft to the plying junction, said guiding means including a loop generating means having a strand snubbing member with a convex surface facing opposite the direction of rotation of the shaft, and fixedly positioned radially outwardly on the shaft, and an idle guiding member, in the form of a roll the surface of which moves freely with the strand, fixedly positioned radially inwardly of the snubbing member, said two guiding members deflecting the strand into a sinuous path which passes over the said convex surface of the snubbing member and over the idle guiding member on the side thereof which leads during rotation of the shaft, the first strand passing directly from the loop into contact with the snubbing member, the length of the zone of contact between the snubbing member and the strand decreasing as the degree of wrap-around of the loop increases.

14. A strand twisting mechanism, comprising: a driven shaft for rotating a loop of a strand, means for feeding the strand into the loop, means for withdrawing the strand from the loop in a run extending at least generally radially of the shaft, and loop generating means fixed with respect to the shaft, said loop generating means including means fixed with respect to the loop generating means for imposing a first retarding tension on the generally radial run of the strand when the loop is of a small size and for imposing a progressively smaller retarding tension on such run as the loop increases in size.

15. A strand twisting mechanism, comprising: a driven shaft for rotating a free-flying loop of a strand, means for feeding the strand into the loop, means for withdrawing the strand from the loop in a run extending at least generally radially into the shaft, loop generating means located radially outwardly of the shaft and fixed with respect to the shaft, said loop generating means including means deflecting and snubbing the outer end of the generally radial run of the strand so as to impose thereon a first retarding tension when the loop is of a small diameter and to impose a progressively smaller retarding tension thereon as the loop increases in diameter.
